CLAIM

The ornamental design for a roof shingle, as shown and described.

DESCRIPTION

FIG. 1 is a front elevational view of a first embodiment of a roof shingle;

FIG. 2 is a front elevational view of a second embodiment of a roof shingle;

FIG. 3 is a front elevational view of a third embodiment of a roof shingle;

FIG. 4 is a front elevational view of a fourth embodiment of a roof shingle;

FIG. 5 is a front elevational view of a fifth embodiment of a roof shingle;

FIG. 6 is a front elevational view of a sixth embodiment of a roof shingle;

FIG. 7 is a front elevational view of a seventh embodiment of a roof shingle;

FIG. 8 is a front elevational view of a eighth embodiment of a roof shingle;

FIG. 9 is a front elevational view of a ninth embodiment of a roof shingle;

FIG. 10 is a front elevational view of a tenth embodiment of a roof shingle;

FIG. 11 is a front elevational view of an eleventh embodiment of a roof shingle;

FIG. 12 is a front elevational view of a twelfth embodiment of a roof shingle;

FIG. 13 is a front elevational view of a thirteenth embodiment of a roof shingle;

FIG. 14 is a front elevational view of a fourteenth embodiment of a roof shingle;

FIG. 15 is a side elevational view of a first and second side of an embodiment of FIGS. 1-14;

FIG. 16 is a bottom elevational view of FIGS. 1, 15, 16, and 30;

FIG. 17 is a bottom elevational view of FIGS. 2 and 17;

FIG. 18 is a bottom elevational view of FIGS. 3 and 18;

FIG. 19 is a bottom elevational view of FIGS. 4 and 19;

FIG. 20 is a bottom elevational view of FIGS. 5 and 20;

FIG. 21 is a bottom elevational view of FIGS. 6 and 21;

FIG. 22 is a bottom elevational view of FIGS. 7 and 22;

FIG. 23 is a bottom elevational view of FIGS. 8 and 23;

FIG. 24 is a bottom elevational view of FIGS. 9 and 24;

FIG. 25 is a bottom elevational view of FIGS. 10 and 25;

FIG. 26 is a bottom elevational view of FIGS. 11 and 26;

FIG. 27 is a bottom elevational view of FIGS. 12 and 27;

FIG. 28 is a bottom elevational view of FIGS. 13 and 28;

FIG. 29 is a bottom elevational view of FIGS. 14 and 29;

FIG. 30 is a top elevational view of FIGS. 15 and 30;

FIG. 31 is a top elevational view of an embodiment of FIGS. 1-14 and 16-29; and,

FIG. 32 is a back elevational view of an embodiment of FIGS. 1-14 and 16-29.
